UNITED STATES PATENT OFFICE.

JOHN PUHL, OF CHICAGO, ILLINOIS.

BOTTLE-CLOSURE.

1,184,568.

Specification of Letters Patent. Patented May 23, 1916.

Application filed April 7, 1915. Serial No. 19,706.

To all whom it may concern:

Be it known that I, JOHN PUHL, a citizen of the United States, residing at Chicago, in the county of Cook and State of Illinois, have invented certain new and useful Improvements in Bottle-Closures, of which the following is a specification.

The object of this invention has been to produce a simple and practical form of bottle closure involving frangible sealing means.

In its preferred embodiment my bottle closure is designed for bluing bottles and embodies as its essential parts a cap member formed with an aperture and having suitable means to engage the neck portion of the bottle whereby to be held securely in place. Beneath said cap member and clamped by it between the cap member and the open portion of the bottle or receptacle is a frangible sealing disk of suitable material susceptible of being readily punctured, the inner surface of said disk being protected by a protective substance such as a layer of paper or similar material prepared in such a manner as to render the same impervious to the action of water or acids according to the nature of the contents of the receptacle in connection with which the invention is used.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a perspective view showing the invention as applied to a bottle type of receptacle. Fig. 2 is a vertical sectional view, the bottle closure being illustrated in normal condition sealing the contents of the receptacle. Fig. 3 is a fragmentary sectional view of the closure portion of the receptacle, dotted lines showing one method of readily puncturing the seal so as to open the bottle and permit of the contents being sprinkled therefrom.

In the drawings A denotes the bottle or receptacle proper and B the cap member of the closure means. The said cap member is connected with the neck portion of the bottle in any substantial manner, and preferably the said bottle neck is formed with a threaded portion as shown at C. The cap member B has a reinforced rolled edge por-

tion which is formed with indentations at intervals in its circumference and such indentations provide projections D capable of engaging with the threaded portion C whereby to facilitate the screwing action of the cap member upon the neck of the bottle and to thus securely hold the closure means in operative position.

At its central portion the cap member B is formed with the aperture E and beneath the cap member is the sealing disk F and the protective member G. The disk F may be made of card-board or any equivalent substance to afford a substantial sealing device. On the other hand the protective member G is preferably a circular piece of oiled paper or similar substance preferably rendered impervious to the action of water or liquids. The parts F and G are of a diameter fitting snugly within the cap member B, and prevented from accidental dislodgment by means of the projections D.

Since the members F and G are frangible it will be apparent that by the use of a pointed tool, nail or similar device, entered into the receptacle A through the aperture E a hole may be punctured in the parts F and G substantially coincident with the opening E and thereupon the contents of the receptacle may be sprinkled or otherwise distributed through such newly made opening. A most convenient means therefore, for rendering the contents of receptacle A distributable is afforded. Furthermore the arrangement of the parts F and G is such that their outermost portions are effectively clamped against the free end of the neck of the bottle and a perfect seal of the contents of the receptacle against deterioration or contamination is effectively supplied under these conditions.

Obviously since the materials from which the members F and G are made are such that when punctured while the continuity of surface of such materials is of course broken by the aperturing of the same, no portions of the said material will fall into the receptacle. In other words, the action of puncturing the members F and G does not cause a separation of any portions thereof from the body of either member and the contents of the receptacle will therefore not receive any such portions of these members, nor is there any likelihood of any such separated portions being created as would cause

liability of clogging of the opening E and interfere with its function as an outlet opening.

Having thus described the invention, what

5 I claim as new is:—

As a new article of manufacture, a closure for bottles and like receptacles, the same consisting of a cap member adapted to fit over the neck of the bottle and having means to 10 attach and detach the same to the neck at will, said cap member being formed with an aperture of a diameter less than that of the bottle neck to which the cap is to be fitted, a frangible member of card-board fitting 15 against the under side of the cap member, and a layer of protective substance consist-

ing of impervious paper removably seated against the inner side of said frangible member, the outermost edges of the frangible member and protective substance being 20 adapted to be clamped between the cap member and the end of the bottle neck and thus held firmly to facilitate the puncturing of said parts but permitting substitution of imperforate protective substance for that 25 punctured as aforesaid.

In testimony whereof I affix my signature in presence of two witnesses.

JOHN PUHL.
